UNITED STATES PATENT OFFICE.

BENJAMIN F. YATES AND FRANK W. COHEN, OF ROCHESTER, MINNESOTA.

DOOR-LATCH.

1,102,313.

Specification of Letters Patent.

Patented July 7, 1914.

Application filed May 1, 1913. Serial No. 764,968.

To all whom it may concern:

Be it known that we, BENJAMIN F. YATES and FRANK W. COHEN, citizens of the United States, residing at Rochester, in the county of Olmsted and State of Minnesota, have invented certain new and useful Improvements in Door-Latches, of which the following is a specification.

Our invention relates to locks and latches and particularly to door latches.

The object of our invention is the provision of a door latch which may be operated not by rotating the knob, but by pushing upon or drawing upon the knob in a direction to open the door.

With door latches now in general use, there are two operations, first the door knob must be turned and then the door pushed open. With our improved lock, the single operation of pulling or pushing draws the latch back and when the latch is released, the door is pulled or pushed open.

Another object of the invention is to provide means whereby the latch may be operated independently of the door knobs so as to permit the latch to move inward on engagement with the keeper plate of the door, as for instance when the door is shoved to.

Other objects will appear in the course of the following description.

Our invention is illustrated in the accompanying drawings wherein:

Figure 1 is a perspective view of a portion of a door with our improved latching apparatus attached thereto, the door of the latch casing being broken away to show the interior parts. Fig. 2 is a horizontal section taken transversely through the door just above the latch bar or bolt. Fig. 3 is a perspective detail view of the elongated gear wheel whereby motion is transmitted from the knob spindle to the latching bolt. Fig. 4 is a fragmentary face view of the outside of the locking casing, the knob bar being shown in section.

Corresponding and like parts are referred to in the following description and indicated in all the *views* of the accompanying drawings by the same reference characters.

Referring to *these* drawings, A designates a portion of a *door* of any usual character, this having an opening in its front edge for the insertion of the latching devices, the interior of the door being recessed at this point as is usual. This opening is

covered by means of the plate 2 which has an opening 3 through which the latch bar 4 projects. This latch bar as illustrated in Fig. 2, comprises a relatively flat bar formed at one end with a laterally offset enlarged head 5, this head having a beveled face 6 and the head having the same area in cross section as the opening 3. The inner face of the bolt or latch bar 4 is formed with 65 teeth 7 and the extremity of the latch bar is formed with an elongated slot 8.

Projecting from one of the casing plates 9 of the casing inclosing the latching apparatus is a guide pin 10 which projects 70 through the slot 8 and which supports the rear end of the latching bolt 4, the forward end of the latching bolt being supported within the opening 3. The inner plate 9 of the lock casing is formed with inwardly 75 bent ears 11 disposed above and below the latch bolt 4, and mounted between these ears is a gear 12 having the form of a rather long toothed cylinder as shown in Fig. 3, which for a greater portion of its length is provided with teeth 13. One end of the cylinder 80 is flattened as at 14 for a purpose to be later stated. That portion of the cylinder which aligns with the flattened portion 14 is adapted to engage with the teeth 7 of the 85 latch bolt 4.

Extending transversely through the side faces of the door is the knob spindle 15. This knob spindle may be either round or square and is formed on one face with teeth 90 16 meshing with the teeth formed on the cylindrical gear 12 as illustrated in Fig. 2. Surrounding one end of the spindle 15 is a sleeve 17 which is locked to the spindle 15 by means of a set screw 18 or in any other 95 suitable manner. This sleeve 17 carries a knob 19 into which the spindle 15 passes. It is to be understood that the sleeve 17 is shiftable through the opening 20 formed in the door and through which the sleeve and 100 spindle pass. Mounted upon the other end of the spindle is a knob 21. Surrounding the spindle is a face plate or escutcheon 22 having a dished central portion 23 forming a seat for a spring 24 which surrounds the 105 spindle 15 and which is disposed between this dished portion 23 and a shoulder 25 formed on the spindle 15 just inward of the knob 21.

Projecting outward from the plate 22 is a 110 tubular fixed sleeve 26, and projecting inward from the knob 21 or from the head 25

is a sleeve 27 slightly larger in diameter than the sleeve 26 and having telescopic engagement therewith. Preferably and as illustrated in Fig. 1, the sleeves 26 and 27 are rectangular in section as is the sleeve 17.

In order to urge the locking bolt 4 outward into projected position, we provide the spring 29 which is attached at one end to a pin 30 projecting out from the casing plate 9 and attached at its other end to a pin 31 illustrated in dotted lines in Fig. 1 and projecting out from the latch bar 4. A pin 32 is also provided on the other face of the latch bar to which the spring may be attached, and a pin 33 is provided under these circumstances for the attachment of the lower end of the spring 29. The reason for providing these two pins 31 and 32 and providing the two pins 30 and 33 is to permit the spring 29 to be shifted from one side to the other when the locking bar 4 is to be reversed in position. The position of the beveled face of the locking bolt or bar will depend, of course, upon the direction in which the door is to open and thus we have provided for this change in the position of the parts to permit of this adjustment.

With the mechanism as before described, it is obvious that if the knob 21 be pushed inward, it will force inward the spindle 15 against the pressure of the spring 24. The movement inward of the spindle will cause a rotation of the cylindrical gear or toothed barrel 12. This in turn will cause a retraction of the locking bolt. The first inward pressure on the knob 21 does not of course act to open the door, but as soon as the bolt has been withdrawn, a further pressure will act to open the door. It will also be seen that pulling upon the knob 19 will cause a like operation, and it will be noted that as soon as pressure or strain is removed from the knob 19, the spring 24 will act to return the parts to their normal position, and that under these circumstances when the beveled face of the bolt 4 strikes the keeper on the door casing, the bolt will be pushed inward and that this inward movement of the bolt will not affect the toothed barrel 13 because of the bolt bearing against the flattened portion 14 of the barrel.

In order to permit the ready insertion of the rack bar 15, the opening for the rack bar is made relatively large and therefore means must be provided for holding the rack bar in contact with the toothed cylinder 12 when the rack bar is in place. To this end we attach to the outside of the lock casing a plate 34. This plate is slotted as at 35 and a screw 36 passed through the slot holds the plate in place. The end of the plate 34 is notched or recessed as at 37 to fit around the rack bar 15 or knob bar. When the plate 34 is drawn outward it will permit the knob bar or rack bar 15 to be laterally shifted out

of engagement with the teeth, but when it is forced inward and held in position by means of the screw 36, it will hold the bar 15 in engagement with the teeth on the cylinder 12 but will not impede the longitudinal movement of the bar 15.

What we claim is:

1. A latching device for doors including a latching bolt, means yieldingly urging the bolt to a projected position, a gear wheel having teeth engaging with the latching bolt, and a knob spindle having teeth meshing with the gear wheel, said spindle extending at right angles to the bolt and through the door.

2. A latching device for doors including a latching bolt having a longitudinally slotted shank, a guide pin passing through the shank, a spring operatively engaging the bolt to project the same, a knob spindle passing transversely through the door and longitudinally shiftable therein, and rotatable means operatively engaging the bolt and the knob spindle whereby an actuation of the latter will cause a projection of the bolt.

3. A latching device for doors including a latching bolt, means yieldingly urging the bolt to a projected position, a gear wheel having toothed engagement with the latching bolt, a knob spindle having teeth meshing with the gear wheel, said spindle extending at right angles to the bolt and through the door, opposed knobs on said spindle, and means on the spindle urging it in one direction.

4. A latching device for doors including a latching bolt, a spring urging the latching bolt to a projected position, a toothed barrel intermeshing with teeth on the latching bolt, a knob spindle extending at right angles to the latching bolt and through the door and operatively engaging the toothed barrel, knobs on the ends of the spindle, and a spring urging the knob spindle in one direction.

5. A latching device for doors including a latching bolt having rack teeth along one face, a toothed barrel, one end of the barrel having a relatively flat chordal face, the remainder of the barrel being longitudinally toothed, a spindle having teeth engaging with the teeth on the barrel, said spindle extending through the door, knobs on the end of the spindle, and a spring urging the spindle in one direction.

6. A latching device of the character described including a latching bolt having a shank, the inner face of the shank being toothed, the knob spindle extending at right angles to the bolt and provided with teeth, a toothed barrel intermeshing with the spindle and with the teeth on the bolt, a spring urging the bolt to projected position, a spring urging the knob spindle in one direction, a knob on one end of the spindle.

sleeve surrounding the spindle and engaged with said knob and movable with the spindle, a knob on the other end of the spindle, a sleeve attached to and movable with the 5 knob and surrounding the spring and spindle, an escutcheon plate through which the knob spindle passes, and a sleeve mounted upon the escutcheon plate and surrounding the inner portion of the knob spindle and 10 having telescopic engagement with the last named sleeve.

7. In a locking device of the character described, a locking bolt having an enlarged head with a beveled face, the body of the 15 bolt being relatively thin to form a shank, the extremity of this shank being longitudinally slotted, a guide pin passing through the shank, a spring for projecting the bolt, means for engaging the spring with either 20 side of the bolt, a knob spindle passing transversely through the door and longitudinally shiftable therein, and a rotatable member operatively engaged by the knob spindle and 25 operatively engaging the shank of the bolt whereby a longitudinal movement of the

knob spindle in one direction will cause a rotation of said member and a retraction of the bolt.

8. A latching device for doors including a latching bolt, means yieldingly urging the 30 bolt to a projected position, a gear wheel having engagement with the latching bolt, a knob spindle having toothed engagement with the gear wheel, said spindle extending at right angles to the bolt and through the 35 door, the opening in the door through which the spindle passes being sufficiently larger than the spindle to permit the latter being shifted out of engagement with the gear wheel, and shiftable means mounted upon 40 the door for holding the spindle in engagement with the gear wheel.

In testimony whereof we affix our signatures in presence of two witnesses.
